UNITED STATES PATENT OFFICE

102,307

DESIGN FOR A LADY'S HANDBAG

Henri Felmann, Chicago, Ill., assignor to Morris, Mann & Reilly, Inc., Chicago, Ill., a corporation of Illinois

Application November 5, 1936, Serial No. 65,716

Term of patent 3½ years

To all whom it may concern:

Be it known that I, Henri Felmann, a citizen of the United States, residing at Chicago, in the county of Cook and State of Illinois, have invented a new, original, and ornamental Design for a Lady's Handbag, of which the following is a specification, reference being had to the accompanying drawing, forming part thereof, wherein

Figure 1 is a perspective view of a lady's handbag showing my new design; Figure 2 is an end view thereof; and Figure 3 is a top plan view of the same.

I claim:

The ornamental design for a lady's handbag, as shown.

HENRI FELMANN.
